SIGNAL MECHANISM

William J. Fant, Jr., South Bend, Ind., assignor
to Bendix Aviation Corporation, South Bend,
Ind., a corporation of Delaware

Application July 7, 1945, Serial No. 603,666

3 Claims. (Cl. 123—198)

1

This invention relates in general to signal mechanism and in particular to a signal mechanism adapted to warn the driver of an automotive vehicle that the engine throttle is being improperly operated.

Now many of the present day automotive carburetors are equipped with a so-called economizer jet operable, when the vacuum of the intake manifold is reduced to or below a certain factor, to increase the combustible mixture within said manifold.

In other words this economizer jet is automatically operative, to inject a supplemental amount of fuel into the intake manifold when and if the gaseous pressure within the said manifold is increased beyond a certain undesirable factor; and this condition is created when the accelerator is improperly operated for example when the accelerator is tramped upon in an effort to effect a quick start of the vehicle.

Now to avoid such an operation of the throttle, which of course results in an uneconomical operation of the engine in view of the waste of gasoline, there is suggested the incorporation, in the power plant of the automotive vehicle, of a manifold vacuum and spring operated motor operable, when the accelerator is improperly operated, to advise the driver of such improper operation.

The principal object of my invention is therefore to provide motor operated means operable, when and if the gaseous pressure within the intake manifold exceeds a certain factor, to advise the driver of the car of the existence of this condition.

Yet another object of my invention is to provide a spring and pressure differential operated motor automatically operable, when the intake manifold vacuum is decreased to a certain factor, to impose a load upon the accelerator pedal resisting a continued opening movement of said pedal.

Other objects and advantages of the invention are further sufficiently referred to in connection with the following detailed description of the accompanying drawing, which represents preferred embodiments of the invention. After considering these examples, skilled persons will understand that many variations may be made without departing from the principles disclosed; and I contemplate the employment of any structures, arrangements, or modes of operation that are properly within the scope of the appended claims.

Figure 1 is a diagrammatic view of a preferred embodiment of my invention;

2

Figure 2 is a diagrammatic view disclosing another embodiment of my invention; and

Figure 3 is a sectional view disclosing details of an automotive carburetor which includes an economizer jet.

Referring now to Figure 1 disclosing a preferred embodiment of my invention the essence thereof lies in a pressure differential and spring operated motor 10 comprising a casing 12, a power element 14 secured in place between the two parts of the casing and a spring 16 housed in a motor compartment 18. As explained below the spring 16 is of a predetermined strength and is interposed between one end of the motor casing and the power element 14; and the compartment 18 is placed in fluid transmitting connection with the intake manifold 20 of an automotive internal combustion engine 22 by means of a conduit 24. The two part motor casing 12 may be secured to the intake manifold by means of a bracket 26. A rod 28, secured to the power element 14, extends through a relatively large opening in the motor casing and through an opening in the bracket, and this opening in the casing places a motor compartment 30 in constant communication with the atmosphere.

One end of the rod 28 is provided with an eye portion 32 through which extends a laterally extending portion 33 of a throttle valve operating lever 34. A throttle valve 35, of Figure 3, operated by the lever 34 constitutes part of a downdraft carburetor 37 of standard design including an economizer jet mechanism 39. The accelerator 36 of the vehicle, connected to the lever 34 by means of a rod 38 and biased to its released position by a spring 40, completes the mechanism of my invention disclosed in Figure 1. It may be added here that the motor 10 in Figure 1 is shown in its deenergized state the spring 16 then serving to move the eye 32 to the right so that the pin 33 of the lever 34 contacts the left end of said eye; and the accelerator and lever 34 are of course at this time in their closed throttle positions.

Briefly describing the operation of the carburetor 37, when the throttle valve 35 is closed the gaseous pressure within the intake manifold 20 is relatively low; accordingly, a compartment 39 within the carburetor is evacuated; for said compartment is connected with the intake manifold by interconnected conduits 41 and 43. The evacuation of the compartment 39 results in a piston 45 being subjected to a differential of pressures thereby moving a stem 47 upwardly said stem being connected to the piston. To the end of 55 the stem 47 there is secured an end plate 49 which

is biased downwardly, by a spring 51, into contact with the upper end of a stem 53 on the end of a valve member 55. The latter member is biased upwardly onto its seat by means of a spring 57. Now when the driver of the car depresses the accelerator to move the throttle 35 toward its wide open position, there is effected an increase in gaseous pressure within the intake manifold and the compartment 39; and this operation automatically results in an expansion of the spring 51 to open the valve 55 when said gaseous pressure reaches a certain critical factor. The latter operation results in a flow of fuel from a float chamber 59 into a discharge nozzle 61 and thence into the induction passage 63. There is thus provided a carburetor including an economizer jet mechanism 31 said mechanism serving to effect an injection of a supplemental amount of fuel into the intake manifold when and if the gaseous pressure within the manifold is increased beyond a certain critical factor, that is a factor permitting the spring 51 to open the valve 55.

Describing now the operation of the mechanism of my invention when the engine is idling the throttle being closed, there is effected a relatively high degree of vacuum that is relatively low gaseous pressure within the intake manifold 20. It follows that under these conditions the compartment 18 of the motor 10 is immediately partially evacuated resulting in the power element 14 being subjected to a differential of pressures; for it is to be remembered that the compartment 30 of the motor is at the time vented to the atmosphere. The power element 14 is then moved to the position shown in dotted lines in Figure 1.

To get the vehicle under way the driver will, after disengaging the clutch and establishing the transmission in the desired gear ratio setting, re-engage the clutch as he depresses the accelerator to open the throttle. Now with a normal operation of the throttle the intake manifold vacuum remains relatively high however if the throttle is opened too quickly then said vacuum is appreciably lowered resulting in an operation of the aforementioned economizer jet mechanism 31 of the carburetor to momentarily increase the fuel supply. This operation is however a costly one in view of the waste of fuel accordingly the mechanism of my invention is employed to advise the driver of his improper operation of the accelerator; for when the manifold vacuum is appreciably lowered, as explained above, then the force from the power element 14, normally acting to collapse the spring 16, is correspondingly reduced and this results in an expansion of said spring. This results in the rod 28 being subjected to a load forcing the same to the right to oppose the physical effort of the driver in opening the throttle through the intermediary of the accelerator. It is to be particularly noted that the size of the power element 14 and the strength of the spring 16 are so selected that the warning mechanism of my invention automatically comes into play when the manifold vacuum is slightly higher than the degree of vacuum necessary to effect an operation of the economizer jet. In other words to render my invention a practical one the signal mechanism comes into play before the damage is done.

It is apparent of course that when the driver senses the additional load on the accelerator pedal he will immediately reduce the throttle opening pressure on said pedal thereby obviating the undesired operation of the throttle. As an additional feature of my invention it is to be noted that the driver may, by compressing the spring 16 by his

physical effort, continue the opening of the throttle after the warning mechanism of my invention has functioned however he would probably then operate the throttle in the proper manner.

Referring now to that embodiment of my invention disclosed in Figure 2 a compartment 42 of a pressure differential operated motor 44, comprising a two part casing 46 and a power element 48, is connected to the intake manifold 50 of an internal combustion engine 52 by a conduit 54. As with the power unit of the preferred embodiment of my invention disclosed in Figure 1, the motor unit 44 includes a spring 56 housed within the compartment 42 said spring acting upon the power element 48. A pin 58, slidably extending through an insulated portion of the motor casing, is connected at one of its ends to the power element and contacts at its other end a movable contact member 60 wired, by a wire 62, to a grounded battery 64. A wire 66, connected to a fixed contact member 68, is connected to a grounded signal light 70 preferably mounted in the instrument panel of the vehicle.

As to the warning operation of the signal mechanism disclosed in Figure 2 it is obviously the same as the heretofore described mechanism of Figure 1. Suffice it to say that when the manifold vacuum is unduly lowered as a result of an improper operation of the accelerator then the power element 48 is moved to the right to bring the movable contact member 60 into contact with the fixed contact member 68 thereby closing the electrical circuit to light the light 70; and the parts of the motor unit and switch are so constructed and arranged that this operation is effected just before the intake manifold vacuum is lowered sufficiently to initiate an operation of the fuel economizer jet.

There is thus provided a very simple yet effective signal mechanism to facilitate an economical operation of the engine of an automotive vehicle of the day. It is to be noted however that the use of this mechanism is not necessarily limited to an automotive vehicle inasmuch as it may be used to control the operation of any throttle control internal combustion engine which is a duplicate or substantial duplicate of the internal combustion engine of an automotive vehicle.

I claim:

1. In an internal combustion engine provided with an intake manifold and a carburetor mechanism comprising a throttle valve and an economizer jet, means for advising the operator of the engine when the gaseous pressure within said manifold reaches a certain critical value said value being slightly below that value which results in an operation of the economizer jet, said means including a pressure differential and spring operated motor unit comprising a casing, a power element within the casing and a spring housed within the casing said spring serving to subject the power element to a certain load when the motor is de-energized; fluid transmitting means interconnecting the motor unit and manifold and means, rendered operative when the power element is loaded by the spring, for advising the operator of the engine of the existence of the aforementioned critical gaseous pressure.
2. In an automotive vehicle provided with an internal combustion engine including an intake manifold, an accelerator and a carburetor mechanism comprising a throttle valve and an economizer jet, means for advising the operator of the engine when the gaseous pressure within said manifold reaches the critical value which results

in an operation of the economizer jet, said means including a pressure differential and spring operated motor unit comprising a casing, a power element within the casing and a spring housed within the casing, said spring, by virtue of its expanding operation, serving to subject the power element to a certain load when the motor is deenergized; fluid transmitting means interconnecting the motor unit and manifold and force transmitting means interconnecting the power element, throttle valve and accelerator, said force transmitting means being so constructed and arranged and so operative that when the power element is loaded by the spring, that is when the motor unit is de-energized, then the operator of the engine is advised, by virtue of said spring loading and the consequent resistance to motion of the accelerator, of the existence of the aforementioned critical gaseous pressure.

3. In an automotive vehicle provided with an internal combustion engine having an intake manifold, an accelerator and a carburetor including a throttle valve and an economizer jet, power means for controlling the operation of the accelerator to resist a certain throttle opening movement thereof which movement would result in an operation of the economizer jet, said power

means including a pressure differential operated motor including a casing and a power element, a fluid transmitting means interconnecting the casing with the intake manifold, a spring within the motor said spring being compressed by an operation of the power element of the motor when said motor is vacuum energized, and force transmitting means interconnecting the throttle, power element and accelerator said force transmitting means including a throttle operating crank, means comprising a lost motion connection interconnecting the power element and crank, and means interconnecting the crank and accelerator.
